Primary Examiner — Rosemary K Tarca(74) *Attorney, Agent, or Firm* — Heisler & Associate(57) **CLAIM**

The ornamental design for an electric wall charger with corner cable, as shown and described.

DESCRIPTION

FIG. 1 is a perspective view of an electric wall charger with corner cable with the contacts extended.

FIG. 2 is a front elevation view of the invention.

FIG. 3 is a bottom plan view of the invention.

FIG. 4 is a top plan view of the invention.

FIG. 5 is a left side view of the invention.

FIG. 6 is a right side view of the invention with the contacts retracted.

FIG. 7 is a rear elevation view of the invention; and, FIG. 8 is a perspective view of the invention with the contacts retracted.

The broken lines in FIGS. 2, 4, 6, 7 and 8 are for purposes of illustration only and form no part of the claimed design.
